UNITED STATES PATENT OFFICE.

JOSIAH BRADLEY, OF BROOKLYN, NEW YORK, ASSIGNOR TO ALBERT WESTLAKE, OF NEW YORK, N. Y.

ELECTRIC OVEN.

1,233,838.

Specification of Letters Patent. Patented July 17, 1917.

Application filed March 21, 1916. Serial No. 85,570.

To all whom it may concern:

Be it known that I, JOSIAH BRADLEY, a citizen of the United States, and a resident of Brooklyn borough, New York city, and State of New York, have invented certain new and useful Improvements in Electric Ovens, of which the following is a specification.

The object of my invention is to provide 10 an improved form of heating oven more particularly intended for use in bottle capping and sealing machines, but applicable to a great variety of uses.

In bottle capping and sealing machines, in 15 which the bottles are to be capped and sealed by means of a fibrous material, it is usual to employ fibrous material in the form of a round disk of such diameter and thickness as may be suitable for the work intended. 20 This disk is folded and pressed into shape around the mouth of the bottle by means of a capping tool mounted on a plunger head. It has been found necessary or desirable in most cases to have this disk preheated, when 25 presented to the capping tool, so as to be sufficiently semi-plastic or moldable to respond readily to the various pressures exerted by the different parts of the capping tool.

The purpose of my invention is to provide 30 a new and improved oven whereby these capping disks are heated on their way to the capping tool.

In the accompanying drawings I have selected the circular form for my improved 35 heating oven for reasons of manifest convenience and have made it inclosed throughout except for a circular opening in the bottom of a size suitable to receive the upwardly moving capping disk. It will be readily 40 understood however, that the shape may be largely varied to suit varying conditions in which the oven may be used.

Figure 1, is a vertical section.

Fig. 2, is a top view.

45 Fig. 3, is a horizontal section on line 3—3 of Fig. 1.

Same letters indicate similar parts in the different figures.

A, is the body of the oven, preferably of 50 metal and formed with an interior heating drum B. Heat is supplied by an electric current from a source of power (not shown) and entering and passing through the oven by the terminals or binding posts a, a, a, a.

The interior drum is held to the oven body 55 by set screws b, b.

When used in a bottle capping and sealing machine this oven is preferably suspended from an arm C, forming part of said machine.

Resistance coils, preferably two in number, are arranged vertically and circumferentially around the interior of the drum B as shown in lines D and may be used either in series or multiple as desired, with a view 65 to the strength of current received from the line wire. Obviously these coils must be so located as not to interfere with the passage of the disk and its operating mechanism.

E, represents a capping disk, which is 70 pushed upwardly into the oven by the elevator plate F, on which it rests and which is operated by devices (not shown) driven preferably by power derived from said capping and sealing machine, until it reaches 75 the position shown in dotted lines in Fig. 1, where it remains during a prescribed period, sufficient to heat the disk to the desired temperature.

The disk is held flat during this operation by a circular guide plate G, provided with a series of blunt points e, e, which rest upon said disk and are held down by the combined weight of the guide plate G and its stem H, which is slidably mounted in the 80 bearing I, secured to the supporting arm C. The downward limit of the play of this stem is controlled by the adjustable nut d and its upward play may be limited either by the top of the oven or by a stop (not shown) 85 interposed in its path at any desired height.

It will be understood that this guide plate and stem are lifted and pushed upward by the elevator plate F, in its upward stroke and that they follow said elevator plate in 90 its downward stroke until stopped by the nut d, coming against the top of the bearing I; the elevator plate with the disk continuing their descent out of the oven, whereupon 95 the heated disk is removed from the elevator plate and a fresh disk substituted.

To secure the proper degree of heat under the varying temperatures of the room or other locality in which the oven is operated, I provide for the admission of fresh 100 air, when required, through the top of the oven.

To this end the top of the oven is pro-

vided with a number of holes or openings *e*, *e*, shown as six in Fig. 2. A damper plate *J* is supported inside the oven by a pin *f*, through the top of the oven and is provided with apertures *g*, *g*, which register with the holes *e*, *e*, when full access of air is desired, but which register only to varying degrees as shown in Fig. 2, when a partial draft is required.

10 This damper is oscillated to admit or cut off the draft, its motion being stopped by one or more pins *h*, *h*, in the slots *i*, *i*, in the damper plate as shown in the dotted lines in Fig. 2. The pin *f* may be used to 15 shift the damper into the desired position.

The operation of my improved oven will be readily understood as follows:

16 The current being turned on and the normal temperature of the oven resulting therefrom being ascertained, the damper is 20 turned, if necessary, to admit sufficient air

to accommodate this temperature to that desired for heating the disk. The driving mechanism is then started and the elevator begins to reciprocate intermittently into and 25 out of the oven as above described.

I claim:—

26 The above described electric heating oven which comprises an electrically heated drum portion, a disk-carrying elevator, reciprocating vertically into and out of said drum, a vertically sliding guide plate adapted to be raised by said elevator and to descend therewith under the action of gravity and a suitable damper whereby the temperature of 30 the interior of said oven is modified as desired.

JOSIAH BRADLEY.
